UNITED STATES PATENT OFFICE.

BENJAMIN M. HOBLICK, OF FRESNO, CALIFORNIA, ASSIGNOR TO BLAKE, MOFFITT & TOWNE, OF SAN FRANCISCO, CALIFORNIA, A CORPORATION OF CALIFORNIA.

PACKING PAD.

Application filed May 15, 1926. Serial No. 109,237.

This invention relates to pads as used for packing purposes in shipment of certain classes of commodities, particularly perishable food products such as fruits and eggs 5 having a high liquid content and easily injured in transportation.

The objects of the invention are to provide a cushion shipping pad of cheap portable construction which will effectively protect 10 the shipment with which it is used, also such a pad which will absorb any liquid which may exude from the shipment, and also which will insure ventilation of the product during shipment.

15 In the drawings accompanying this application I show one form of my invention that it is to be understood that modifications thereof may be made within the scope of the invention and appended claims.

20 The drawings show in Figure 1 a perspective view of one of my improved pads, Figure 2 in perspective, the under side of the pad of Figure 1, Figure 3 an enlarged substantially full size fragmentary section of my pad, and 25 in Figure 4 a strand of the packing material substantially full size.

In further detail the pad comprises a sheet 25 of paper 1 perforated at 2 and with its margins 3 folded over to form retaining edges for the packing material 4. This packing material is preferably strips or shreds of cheap grade of tissue paper all rumpled up so as to bulk to maximum, and it is arranged evenly upon the perforated sheet 1 to any depth desired, usually about as shown in Figure 3, and retained in place by several tapes or bands 5 extended either under the margin 3 as dotted at 5', or over the margin to the underside of the pad as indicated at 5" and 40 the ends gummed in place.

In forming the perforations 2 in the paper sheet 1 I preferably punch them from one side without cutting out their disks so that the edges of paper around each hole will extend 45 outwardly of the finished pad as shown at 2' in Figure 3 as this greatly assists the ventilation by holding the sheet more or less spaced from the boards or slots of the shipping box

or crate in which the pad is used, thus providing more or less broken channels for circulation of air.

In use the shipping box is lined with the pads, or one placed top and bottom of the food product with perforated paper side against the box, and the product placed on 55 or between the rumpled tissue padding.

This pad formed by rumpled tissue strips has been found very effective in protecting such shipments of such products as grapes and other fresh juicy fruit, for the highly 60 absorbent nature of the tissue combined with the ventilating feature effectively prevents molding through juicy exudations, and the tissue is free from fine particles likely to adhere to the product to cause annoyance to 65 the consumer.

It is of course understood that the thickness or size of the pad may be varied to suit the particular use to which it is put.

I claim:

1. As an article of manufacture, a portable packing pad adapted to be placed in a fruit shipping box, said pad comprising a sheet of paper with its margins turned over to form a retaining lip extending entirely around the 70 edge of the pad, a layer of rumpled tissue paper shreds in pad formation arranged on the sheet and retained at the edges of the pad by said lip, a relatively narrow tape passing over the paper shreds and secured at its ends 75 to the sheet, and with said shreds freely exposed between the tape and said lip.

2. As an article of manufacture, a portable packing pad, composed of rumpled tissue paper strips held in pad formation by means 80 of a sheet of perforated paper on one side; said perforations being punched to break the material out into small, upstanding lips surrounding the hole, the margins of said perforated paper being folded over to form a retaining edge for the tissue paper strips, and 85 said margins being held in position by bands passing over the exposed rumpled tissue paper.

BENJAMIN M. HOBLICK.
